[57] CLAIM

[21] Appl. No.: 700,904

The ornamental design for a signalling warning light for vehicles, as shown and described.

[22] Filed: May 16, 1991

DESCRIPTION

[52] U.S. Cl. D10/114; D26/32

FIG. 1 is a front elevational view of the signalling warning light for vehicles showing my new design and the wires broken away to indicate indeterminate length; FIG. 2 is a rear elevational view thereof;

[58] Field of Search D10/104, 109, 111, 114, D10/115; D26/28, 29, 30, 31, 32, 33, 34, 35, 36, 362/61, 62, 72, 227, 235, 237, 240, 282, 362, 367, 368

FIG. 3 is a left side elevational view thereof; FIG. 4 is a right side elevational view thereof; FIG. 5 is a top plan view thereof; and, FIG. 6 is a bottom plan view thereof.
